(57) **CLAIM**

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The figures show features in of an article of footwear with dot-dot-dash broken lines that form no part of the claimed design. Further, the dot-dot-dash broken lines immediately adjacent the portions shown in solid lines form the boundary of the design, with the broken lines forming no part of the claimed design. The even length broken lines in the figures depict stitching, which forms part of the claimed design.

1 Claim, 7 Drawing Sheets
